INVENTOR.

George D. Frederick

BY

George Baldwin

ATTORNEY.

UNITED STATES PATENT OFFICE

GEORGE D. FREDERICK, OF DETROIT, MICHIGAN

TOY

Application filed January 16, 1930. Serial No. 421,154.

This invention relates to improvements in toys, and refers more particularly to rocking toys for exercising.

It is an object of the invention to provide a toy having a member pivotally mounted and adapted to swing up and down, and to provide both a seat and stirrups at different distances from the axis of the member, and a spring which exerts upward pressure against the underside of the member intermediately of its length, so that when the rider throws his weight on the seat the member moves downwards and compresses the spring, and when the rider throws a portion of his weight upon the stirrups the spring swings the member upwardly about its axis.

Another object of the invention is to provide such a toy wherein provision is made for setting the spring at varying distances from the axis of the member so that it may be positioned to offset riders of different weights.

With these and other objects and advantages in view which will become apparent as the specification proceeds, the invention is hereinafter more fully described with the aid of the accompanying drawings, in which:

Figure 1 illustrates a side elevation of the invention, and

Figure 2 is a plan view thereof.

Figures 3 and 4 show enlarged details of the mounting arrangement of the upper and lower ends of the spring.

Figure 5 is an enlarged plan view of the upper spring plate, with a portion of the spring in section, and the supporting means for the said plate.

Figure 6 is an enlarged inverted plan view of the lower spring plate and the supporting means therefor, showing a portion of the spring in section.

Referring to the drawings, 1 designates a base plate preferably supported at its extremities on rests 2. Extending upwardly from the plate 1 adjacent one end of the latter is a support 3 the lower extremity of which is preferably flexed horizontally at 4. The horizontally flexed portion 4 is secured to the base plate 1. To the support 3 adjacent its upper end one portion of a hinge 5 is so secured that its other portion may swing

about a horizontal axis. The said other hinge portion is fastened to one end of a member 6 which extends longitudinally over the base plate 1. At the outer free end of the said member a seat 7 is formed, depending from the member on both its sides and intermediately of its length are rigid stirrups 8, and extending upwardly from the member also intermediately of its length is a projection 9. The latter is preferably positioned substantially centrally of the width of the said member 6 and, in the present instance is shaped to present the appearance of an animal's head. Laterally from this projection opposed handles 10 extend.

The stirrups 8 preferably consist of flat metal strips flexed inwardly at their upper extremities for attachment to the member 8 and flexed outwardly at their lower extremities 8b to provide foot rests. The projection 9 is usually supported on the member 6 by angle plates 9a.

Against the underside of the member 6 intermediately of its length two parallel spacing members 11 are longitudinally arranged, and under the spacing members 11 two parallel guides 12 are secured. It will be noted that the adjacent sides of the spacing members 11 are positioned further apart than the adjacent sides of the guides 12. 14 designates a spring the ends of which are secured, usually welded, to an upper and a lower slide 15 and 19 respectively.

The upper slide 15 rests against the undersides of the guides 12. Bolts 17, the heads 17a of which lie between the spacing members 11, extend downwardly between the guides 12 and through apertures formed through the slide 15 towards its ends and substantially centrally of its width, and have nuts 18 secured to their lower extremities.

In the base plate 1 a longitudinal recess 1a is formed intermediately of its length. On the plate a pair of parallel guides are longitudinally arranged so that their adjacent margins extend over the margins of the slot 1a. The lower slide 19 is slidable on the guides 20. Bolts 21, the heads 21a of which lie in the recess 1a, extend upwardly between the guides 20 and through apertures formed

through the slide 19 towards its ends and substantially centrally of its width; these bolts 21 have nuts 22 secured to their extremities.

By loosening the nuts 18 and 22 the slides 5 15 and 19 may be so set that the spring 14 bears against the underside of the member 6 at varying distances from the hinge 5. Thus the toy may be adjusted for use by children 10 of vastly different weights. It will also be noted that the stirrups 8 are so positioned that a rider may readily throw his weight onto them and off the seat 7 thereby lessening 15 the leverage on the spring 14 and permitting the latter to swing the member 6 upwardly.

While in the foregoing the preferred embodiment of the invention has been described and shown, it is understood that the construction 20 is susceptible to such alterations and modifications as fall within the scope of the appended claims.

What I claim as my invention and desire to secure by Letters Patent is:

1. In a toy of the character described, the 25 combination of a base, a member pivotally mounted thereover to swing about a horizontal axis, guides arranged longitudinally on the underside of said member, other guides arranged longitudinally on said base, a spring, slides secured to its extremities, one 30 slide being movable longitudinally on the guides on the underside of said member and the other slide being longitudinally movable along the guides on said base, and a seat on 35 said member.

2. In a toy of the character described, the 40 combination of a base, a member pivotally mounted thereover to swing about a horizontal axis, a seat adjacent the outer end of said member, opposed stirrups depending from 45 said member between its pivotal mounting and said seat, handles carried above said member, guides arranged longitudinally on said base, other guides arranged longitudinally on 50 said member, a spring, a slide secured to each end of said spring, each slide being longitudinally movable on one set of guides, and separate means cooperating with each slide for securing it at the desired position along 55 the member or base.

3. In a toy of the character described, the 60 combination of a base, an upright mounted thereon, a member pivoted on said upright so as to turn about a horizontal axis, a seat adjacent the outer end of said member, a slide movable longitudinally on said base, a second slide longitudinally movable on the underside of said member, a spring each extremity 65 of which is secured to one of said slides, and separate means for holding each slide against accidental movement relative to its member or base.

4. In a toy of the character described, the 70 combination of a base, an upright mounted thereon, a member pivoted on said upright 75 so as to turn about a horizontal axis, a seat adjacent the outer end of said member, a slide movable longitudinally on said base, a second slide longitudinally movable on the underside of said member, a spring each extremity of which is secured to one of said slides, and separate means for holding each slide against accidental movement relative to its member or base.

so as to turn about a horizontal axis, a seat adjacent the outer end of said member, a slide movable longitudinally on said base, a second slide on the underside of said member movable longitudinally of the latter between the 70 pivotal mounting of the member and said seat, a spring each extremity of which is secured to one of said slides so that the vertical distance of the spring from the upright may be varied, and opposed stirrups depending from said member nearer its pivotal mounting than said seat.
